HENRICK J. HJORTH, OF WOBURN, MASSACHUSETTS.

GRINDING ATTACHMENT.

1,293,435.

Specification of Letters Patent.

Patented Feb. 4, 1919.

Application filed November 9, 1916. Serial No. 130,368.

To all whom it may concern:

Be it known that I, HENRICK J. HJORTH, a citizen of the United States, residing at Woburn, in the county of Middlesex and State of Massachusetts, have invented new and useful Improvements in Grinding Attachments, of which the following is a specification.

The present invention relates to grinding machinery and has for its particular object to provide an accurately mounted and arranged power driven grinding spindle carrying a grinding wheel and arranged in such a manner that it may be mounted as an attachment to machines of various sorts, such for example as complete organized grinding machines, bench lathes, and other machine tools and machines. My invention resides both in the machine or instrument designed and arranged as an attachment, and also in the construction, design, and arrangement of a grinder spindle and its mountings, adapted not only to serve as an attachment to a machine tool, as has been above indicated, but also as the spindle of a grinder in other arrangements. In the drawings which show the preferred present embodiment or form of my invention—

Figure 1 is a perspective view of the 30 grinder attachment complete.

Fig. 2 is a longitudinal sectional view through the bearing of the grinder spindle showing the spindle partly in elevation and partly as being broken away.

Fig. 3 is a section of the central part of the bearing taken on a longitudinal plane at right angles to that of the section shown in Fig. 2.

Fig. 4 is an elevation of the rear end of the 40 spindle and its bearing.

Fig. 5 is a cross section of the spindle and bearing on line 5—5 of Fig. 2.

The same reference characters indicate the same parts in all the figures.

In the drawings 6 represents a base on which are mounted brackets 7 and 8, the former having a bearing 9 in which is a countershaft carrying pulleys 10 and 11, and the other having a sleeve 12 in which is a grinder 50 spindle 13. Said brackets or heads 7 and 8 are adjustable on the base and have clamping bolts 14 passing through the foot portions of said brackets into undercut longitudinal slots 15, 16 and carrying securing nuts 17. They 55 have also provision for vertical adjustment, the part of each bracket which carries the

bearing being a separate piece arranged adjustably on the foot part. Pulley 10 is driven by belt 18 which derives its motion from any convenient external source of 60 power while the pulley 11 drives a belt 19 which passes around a pulley 20 on the grinder spindle 13 and drives the latter.

The end of the spindle 13 has a bore or deep socket 21 terminating in a threaded portion which receives the shank 22 of a grinding wheel or tool 23, the extreme inner end of said shank being threaded at 24. Preferably the socket 21 and the part of the shank which enters the same are complementally tapered 70 so as to provide a secure and rigid mounting of the shank in the spindle.

The bearing for the spindle 13 is removable from the sleeve 12. When in place in the latter it is secured by clamping screws 75 25 which pass through ribs 26 on opposite sides of a longitudinal slot in the side of the sleeve and close said sleeve tightly upon the bearing. Said bearing comprises two cylindrical blocks 27 and 28 centrally bored to receive the shaft. The block 27 has an extension 29 at one end on which the adjacent end of the block 28 is screwed, and in such extension is a shoulder 30 abutting against an enlargement or collar 31 on the spindle. 80 The other block has a web 32 adapted to bear against the opposite end or face of the enlargement 31; the shoulder 30 and web 32 forming end thrust bearings which co-act with the enlargement 31 to prevent endwise 85 movement of the spindle. Looseness or end shake in the thrust bearing may be taken up by adjusting one of the blocks upon the other, the proper adjustment being securely maintained by a locking ring or nut 33 which is 90 screwed upon the extension 29 and bears against the end of the block 28.

The spindle has a central lateral bearing in the extension 29 and in the adjacent part of the block 27. Its ends have their bearings 100 in bushings 34 and 35 which fit closely upon the spindle and are entered into coaxial sockets 36, 37 in the blocks. Nuts 38, 39 are screwed on the outer ends of said bushings, and are set against shoulders adjacent to the 105 ends of the blocks 27 and 28 and have lips 40 which are overlapped by the inner edges of retaining rings 41 which surround these heads and are secured to the blocks by screws 42, as clearly shown in Fig. 2. The bushings are prevented from turning by screw studs 43 removably fitted in tapped holes in

the blocks and having key ribs on their inner ends entering slots 44 in these bushings. The flat sides of said key ribs engaging the sides of the keyways prevent the studs from turning and can not accidentally become dislodged when the bushings are in place.

For lubrication there is provided an oil hole 45 entering the socket 37 through the side of the block 28, a similar hole 46 entering the socket 36 through the side of the block 27 and a third oil hole 47 through the block 27 intersecting one of several passages 48 through the extension part 29 of the block 27 running from the socket 36 to the end of said extension. Passages 48 conduct oil to the enlargement 31 and the thrust bearing shoulder 30. In the web 32 are passages 49 from the socket 37 which admit oil to the bearing surface of said web. All of the oil holes are closed by screw plugs 50 which are removable at need. Each of the sockets is enlarged between its ends, and at its extreme inner end, to provide annular chambers containing oil. Preferably the larger of the chambers in each socket contains a body of absorbent material, such as felt, to soak up and retain the oil. The bushings 34 and 35 have a number of longitudinal slots in which are contained wicks 51 to soak up oil and continuously feed it to the adjacent surface of the spindle, and in the outer portion of the key way 44 is a similar wick 52 for lubricating the end of the bearing.

A most important feature of the invention consists in the fact that the bearing bushings may be adjusted with the utmost ease to take up wear. Their outer surfaces are tapered as shown in the sectional views, and the inner walls of the sockets in the blocks are complementally tapered, except that those portions which are enlarged to form oil chambers as previously described; the extent of contact between the surfaces of the bushings and sockets being sufficient for the purpose of compressing the bushing upon the spindle. The keyway 44 in each bushing extends the entire length of the bushing so that the latter is in effect a split sleeve. Consequently, then, by forcing these externally tapered split sleeves into the sockets more or less they can be sprung so as to fit more or less closely upon the spindle, and may thus be adjusted to take up looseness as they wear. The nuts 38 and 39 serve as the means for so adjusting the bushings. Such nuts project beyond the retaining rings 41, as shown in Fig. 2, and are flattened at opposite sides as shown in Fig. 4 so that they may be turned by a wrench. The retaining rings serve as the abutments against which the lips 40 of the nuts bear when the latter are turned to adjust the bushings so as to take up wear. Thus any side shake of the spindle may be

eliminated as soon as it occurs by simply turning one or both of the nuts 38 or 39 without dismantling the fixture, and even while the spindle is running. Particularly it is to be noted that the adjustment of these bushings does not alter the position of the grinding wheel in the slightest.

It will be apparent that the elements hereinbefore described constitute a simple and accurate means for mounting a grinding tool, one which can be applied in a variety of ways according to the purposes for which it is used. An especially useful feature resides in the accuracy of the means for mounting the grinding spindle, which is the most important aspect of any grinding machine. The bearing elements or members for the spindle, by which its accurate location and running are secured, consists of the bushings 34 and 35, mounted in a rigid holder. These bushings engage the spindle near its extreme ends, thereby making it as steady as possible, and are readily removable, whereby others may be substituted when those previously in place become worn out. The fact that the bushings are so small and easily removable makes their replacement when worn a matter of the utmost simplicity and of the most trifling expense. The end thrust bearing is another important feature, as it securely holds the spindle against displacement in either direction, and is adjustable in a simple manner to take up end shake. The position of the end thrust bearing between the lateral bearings enables the latter to be placed at the ends of the spindle; while the lateral bearings are entirely independent of the end thrust bearing and are susceptible of adjustment without affecting the latter.

What I claim and desire to secure by Letters Patent is:

1. A grinding attachment comprising a base, a bracket mounted on said base having a sleeve portion, bearing blocks coupled together contained in said sleeve portion and a spindle rotatably mounted in said bearing blocks, the spindle having an end thrust collar and the bearing blocks being relatively adjustable and having abutments engaging opposite ends of said collar.

2. A grinding attachment comprising a pair of alined bearing blocks one of which is screwed upon the other, a grinder spindle having lateral bearings in said blocks and having an enlargement between the blocks, and each of said blocks having an abutment or bearing surface engaging one of the ends of said enlargement.

3. The combination of a spindle, axially alined bearing blocks containing said spindle, one of said blocks being screwed upon the other and adjustable endwise with respect thereto, bushing detachably contained in the blocks through which the spindle

passes, and said blocks having adjacent shoulders and the spindle having an enlargement located between said shoulders constituting an end thrust bearing.

- 5 4. A grinder spindle having an enlargement between its ends, a holder for said spindle having end thrust bearing surfaces engaging opposite end faces of said enlargement, and side bearings, each of uniform
 10 diameter internally throughout its entire length, for the spindle adjacent to the ends of the latter on each side of said enlargement.

5. The combination of a spindle, a block
 15 in which said spindle is rotatably contained having a socket at one end with a tapered internal surface, a longitudinally split bushing surrounding the spindle entering said socket and having an externally tapered surface
 20 fitting the tapered surface of said socket, a nut screwed upon the bushing and abutting against the end of the block, and a retainer secured to said block overlying a portion of said nut to retain the same in
 25 place and serve as an abutment for the nut.

6. The combination of a spindle, a block
 in which said spindle is rotatably contained having a socket at one end with a tapered internal surface, a longitudinally split bushing surrounding the spindle entering said
 30 socket and having an externally tapered sur-

face fitting the tapered surface of said socket, a nut screwed upon the bushing and abutting against the end of the block, a retainer secured to said block overlying a portion of said nut to retain the same in place and serve as an abutment for the nut, and means for restraining the bushing from rotation relatively to the block.

7. The combination with a grinder spindle having an enlargement, blocks adjustably connected together having end thrust surfaces respectively engaging opposite ends of said enlargement, and lateral bearing bushings entering the outer ends of said blocks and fitting the spindle, said bushings being independent of the end thrust bearing.

8. The combination with a grinder spindle having an enlargement, blocks adjustably connected together having end thrust surfaces respectively engaging opposite ends of said enlargement, and lateral bearing bushings entering the outer ends of said blocks and fitting the spindle, said bushings being externally tapered and the portions of the blocks wherein they are received being complementally tapered, and means for adjusting said bushings endwise to compress them toward the spindles for taking up wear.

In testimony whereof I have affixed my signature.

HENRICK J. HJORTH.
